UNITED STATES PATENT OFFICE.

ROY E. BROWN, OF PORTLAND, OREGON, ASSIGNOR OF FORTY-NINE PER CENT TO
PERCY C. CAFFEE, OF PORTLAND, OREGON.

LOCK.

Application filed July 27, 1927. Serial No. 208,854.

This invention relates to door locks and has special reference to locks of the type shown in Letters Patent, No. 1,342,157, granted to me June 1, 1920. The present 5 invention provides an improved means for preventing the retraction of the bolt from the outside of the door and also provides improved means for setting the tumblers whereby the pull bar may be actuated to 10 retract the bolt from the outside of the door. The invention also provides an improved form of bolt whereby the bolt may be reversed accordingly as the door swings to the right or the left. The invention is illustrated 15 in the accompanying drawing and consists in certain novel features which will be first fully described and then more particularly defined in the appended claims.

In the drawing:

20 Figure 1 is an elevation, partly in section, of a lock constructed in accordance with the present invention, the face plate of the lock being removed;

25 Fig. 2 is a vertical section on the line 2—2 of Fig. 1, and

Fig. 3 shows the dead latch in detail.

The lock case 1 may be of the usual form and the bolt 2 is slidably mounted in the upper portion of the case, as shown clearly 30 in Fig. 1. The head of the bolt is supported by a slot in the end of the casing in the usual manner and the shank 3 is provided with a longitudinal slot 4 through which a supporting pin or rod 5 passes to guide the 35 bolt and prevent it dropping within the lock case. The pin 5 is, of course, secured at its ends in the face plates of the lock casing and passes through the slot 4 so that it serves as a support and a guide for the bolt and also 40 as a means to limit the movement of the bolt whereby jamming of the parts and consequent bending thereof will be avoided. The shank 3 is provided with a socket 6 in its inner extremity to receive one end of an 45 expansion spring 7 which is held by the said socket and bears against the end of the lock casing, as clearly shown in Fig. 1, so that it tends constantly to project the bolt, and between the inner end of the slot 4 and the said 50 socket 6 the upper and lower edges of the bolt are shaped to provide notches 8 and define shoulders 9, the function of which will presently appear. The inner end of 55 the bolt head 2 is formed with notches 10 which define sockets adapted to receive the

correspondingly shaped enlargement 11 at the outer end of a drawbar or lever 12 so that the said drawbar or lever will be held in engagement with the bolt and will travel with it. It will be readily noted that the 60 enlarged end of the drawbar may be engaged in either socket 10 and will be held therein by the sides of the casing so that the bolt may be reversed when necessary and will operate in the same manner which- 65 ever edge of the bolt is uppermost.

The drawbar 12 is intended to be actuated by tumblers 13 mounted in the lower portion of the lock case. These tumblers in the present lock are carried by the knob spindle 70 14 which passes through the lock and through the door 40 and is equipped at each end with a knob 15. The outer tumbler 13 is mounted directly upon the spindle so as to rotate therewith and is constructed with 75 an extended hub member 16 having a flat- sided bore whereby it will be caused to turn with the spindle while the intermediate and inner tumblers are loosely mounted upon a sleeve or bushing 17 which is carried by the 80 inner face plate of the lock, as shown in Fig. 2, the bushing being inserted through the said face plate from the outer side thereof and then upset against the same, as shown 85 at 18. The several tumblers are separated by 85 spacing washers 19 and are provided upon their opposed faces with lugs 20 whereby the combination of the lock may be varied and operated in the same manner as set forth in my above mentioned patent. The tumblers 90 are constructed in their peripheries with notches 21 to be engaged by the beak 22 of the drawbar 12 when the bolt is to be re- tracted from the outside of the door through the manipulation of the tumblers, it being 95 understood that when the tumblers have been properly operated according to the combina- 100 tion of the lock, the several notches 21 will be brought into alinement below the beak 22 which will then at once drop into engage- 105 ment with the notches. On the outer face of the outer tumbler 13, there is provided a ratchet or notched disk 23, the notches of which correspond in number and arrange- 110 ment to the lug receiving openings 24 in the tumblers, and this disk is engaged by a re- silient pawl 25 secured at one end in the lock case and engaging the notches in the periph- ery of the said disk so that as the disk and the tumbler are rotated the pawl will make 110

a clicking sound as it moves into engagement with the successive notches. The operator will be thereby enabled to operate the combination of the lock in the dark by counting 5 the clicks, and it will not be necessary for him to read the dials 26 which are provided upon the knob spindle adjacent the inner end of each knob hub. It will be understood that when the tumblers are not set in accordance 10 with the combination there will always be at least one tumbler presenting a portion of its periphery across the notches of the other tumblers and, consequently, the drawbar 12 cannot drop into engagement 15 with the tumblers and rotation of the knob spindle by one who does not know the combination will not affect retraction of the bolt.

The drawbar 12 is, of course, disposed between the bolt and the tumblers, as shown in Fig. 1, and it is provided upon its upper edge with a shoulder 27 adapted to be engaged by a dog or dead latch 28 which is pivotally mounted in the lock case whereby it may be so disposed that its free end will 20 abut the shoulder 27, as shown in Fig. 1, and thereby prevent retraction of the drawbar and, of course, prevent retraction of the bolt. The turning shaft 29 of this dead latch or dog is extended through the inner side 25 of the lock and equipped with any convenient form of handle 30 whereby it may be pivotally swung when desired, and within the lock a brake spring 31 is mounted having its free end 32 arranged to bear upon the pivoted end of the dog so that the dog will be yieldably held in any position to which it may be turned, and it may be here noted that the dog is of such dimension and so located that if it be turned to a horizontal position 30 as shown in Fig. 1, it will abut the shoulder 27 and prevent operation of the lock while if it be swung upwardly it will play in a notch 8 of the bolt and bear against the shoulder 9 so that it will retract the bolt 35 against the tension of the spring 7, the drawbar 12 then riding idly on the peripheries of the tumblers. As the handle 30 is at the inner side of the door, it will be seen at once that the door may be always opened from the 40 inside and the person can never be locked in the room.

The dead latch is provided with trunnions or journals 32 on its side edges at its pivoted end which are rotatably engaged in openings 45 provided therefor in the sides of the lock casing and slots or notches 33 extend diametrically across the trunnions to be engaged by a diametrically disposed lug 34 on the turning shaft 29 whereby the lock may be 50 fitted to a door swinging either to the right or to the left without shifting the latch. The turning shaft, as shown clearly in Fig. 3, is formed with a reduced terminal portion 35 adapted to pass into an opening 36 55 through the dead latch concentric with the

trunnions 32 so that the axial alinement of the shaft and the trunnions will be maintained and the bending strain upon the shaft and the lug 34 will be minimized. The outer portion of the shaft is rotatably mounted in the inner escutcheon plate 37 and is held against endwise movement by the handle 30 at one side of the plate and by a washer and cotter pin, indicated at 38, between the other side of the plate and the door. 75

Having thus described the invention, I claim:

1. In a lock, the combination of a bolt, a drawbar connected therewith, a plurality of tumblers disposed below the drawbar and arranged to be engaged thereby, a knob spindle, a hub member fixed to the outer tumbler and engaged with the knob spindle whereby to rotate therewith, a bushing fitted around said hub member and held against rotation, the intermediate and outer tumblers being loosely mounted upon said bushing, a ratchet fixed to the outer face of the outer tumbler, and a detent engaging said ratchet disk. 85

2. In a lock, the combination of a bolt provided with a head and a reduced shank extending inwardly from the head, the bolt being provided with sockets at each side of the shank, a drawbar engageable in either socket to move with the bolt, a plurality of tumblers disposed below the drawbar to be engaged thereby for withdrawing the bolt, means yieldably holding the bolt projected, and a latch member mounted between the bolt and the drawbar and engageable with the drawbar to maintain the bolt projected or with the bolt to retract the bolt. 95

3. In a lock, the combination of a slideable bolt having notches and transverse shoulders on its upper and lower edges, means for yieldably holding the bolt projected, a drawbar engageable with the bolt to move therewith, a plurality of tumblers disposed below the drawbar and engageable thereby for retracting the bolt, and a latch member pivotally mounted between the bolt and the drawbar and engageable with the drawbar in one position to prevent retraction of the bolt and in another position engageable with the shoulder on the bolt to retract the same. 105

4. In a lock, the combination of a slideable bolt, means for yieldably holding the bolt projected, a drawbar disposed below the bolt and engageable therewith to move with the bolt, said drawbar having a shoulder on its upper edge, a plurality of tumblers disposed below the drawbar to be engaged thereby for retracting the bolt, and a latch member pivotally mounted between the bolt and the drawbar and adapted in one position to engage the shoulder on the drawbar and prevent retraction of the bolt and in another position to engage the bolt and retract the same. 115

5. In a lock, the combination of a slideable bolt, a drawbar fitted to the bolt to move therewith, means for actuating the drawbar to retract the bolt, a dead latch between the bolt and the drawbar engageable with the bolt to retract the same or with the drawbar to prevent retraction of the bolt, said latch having trunnions journaled in the case of

the lock and constructed with diametrical notches, and a turning shaft rotatably supported at one side of the lock and having a lug engageable in the notch in either trunnion of the latch.

In testimony whereof I affix my signature.

ROY E. BROWN. [L. S.]
